CLAIM

The ornamental design for a wall mounted exercise rack, as shown and described.

DESCRIPTION

FIG. 1 is a top, front, right perspective view of a wall mounted exercise rack showing my new design;

FIG. 2 is a front view thereof;

FIG. 3 is a right side view thereof;

FIG. 4 is a left side view thereof;

FIG. 5 is top view thereof; and,

FIG. 6 is a top, front, left perspective view thereof, positioned on a wall shown as example environment.

The wall shown in broken lines in FIG. 6 is for the purpose of illustrating environmental structure, which form no part of the claimed design.

The uneven-length broken lines immediately adjacent to the shaded area define the bounds of the claimed design and form no part thereof. The even-length broken lines depicting the remainder of the wall mounted exercise rack show portions that form no part of the claimed design.
